[57] CLAIM

The ornamental design for an automobile security assembly for preventing the rotation of the steering wheel or theft of the air bag, as shown and described.

DESCRIPTION

FIG. 1 is a top, front, and left side perspective view of an automobile security assembly for preventing the rotation of the steering wheel or theft of the air bag showing my new design;

FIG. 2 is a front elevational view thereof;

FIG. 3 is a bottom plan view thereof;

FIG. 4 is a rear elevational view thereof;

FIG. 5 is a top plan view thereof;

FIG. 6 is a right side elevational view thereof; and,

FIG. 7 is a left side elevational view thereof.
